UNITED STATES PATENT OFFICE

EMIL DIETZE, OF RICHMOND HILL, NEW YORK, ASSIGNOR TO AMERICAN CASTING AND MANUFACTURING CORPORATION, OF BROOKLYN, NEW YORK, A CORPORATION OF NEW YORK

SEAL PRESS

Application filed January 16, 1930. Serial No. 421,087.

This invention refers to a seal press for flattening steel and other metallic seals and imparting raised characters or impressions thereto. It is primarily adapted for use with 5 ring seals of the kind exemplified in my former Letters-Patent No. 1,575,418, dated March 2, 1926, for hasp seals.

Such a metal seal for protective locking means for a box or container fastened by a 10 hasp and staple, constitutes the member which passes through the eye or loop of the staple in effecting the interlocking of said hasp and staple, such seal being therefore a substitute for the ordinary pin, bar, or padlock used 15 with the loop of the staple; and after the seal has been inserted through the staple and against the hasp or clasp which overlaps the staple, a sealing impression is suitably imparted to said sealing member by means of 20 the press in order to so spread or distort the inserted portion of the sealing member as to render the seal non-withdrawable from the hasp, except by breaking, and entirely non-removable therefrom; whereby it becomes im- 25 possible to remove and replace the seal intact, and thus any removal of the seal which may be attempted will necessarily involve its de- struction beyond the possibility of reuse.

And the invention, therefore, comprises 30 essentially the construction, combination and arrangement of parts, substantially as will be hereinafter described and claimed.

In the annexed drawings illustrating my invention:

35 Figure 1 is a sectional side elevation of my improved seal press, with the jaws open and receiving a seal carried on a coin box in readiness to be pressed.

Figure 2 is a top plan view of my improved 40 seal press, the operating handle being indicated only in section.

Figure 3 is an enlarged sectional detail 45 view of part of the press and a seal when it is being held in position by its gauge or guide and in proper relation to the lower die before said seal has been flattened and im- pressed.

Figure 4 is a detail plan view of one of the 50 ring seals after being flattened and impressed in the operation of the press.

Similar characters of reference denote like parts in all the different figures of the drawings:

7 denotes a box or receptacle for cash, valuables or the like, the same being merely indicated in outline as a specimen. It has a hinged lid 8, that is provided with a hinged hasp 9, consisting of a short clasping plate or strap hinged at 9a, said hasp being provided with the usual vertical slot to receive the staple 55 or loop 10 that is fastened rigidly to the wall of the box 7, see Figure 1.

The box 7 represents only one example of a great variety of receptacles or compartments employing a hasp fastener with some form of loop or staple for locking purposes, which staple generally has some kind of a ring or a pin, or a padlock or any other locking contrivance passed through the same, the effect of which will be to keep the hasp in position over the 60 staple. Examples of compartments, boxes, or receptacles thus secured are safe-deposit boxes, coin boxes and cash drawers in slot-machines and pay-telephones, mail bags and 65 pouches of various kinds, to which a hasp and staple may be applied, which hasp and staple may vary within very widely separated limits in order to accommodate the need and supply an effective fastener. The sealing element 70 which is compressed by the press is inserted in the staple, and the inserted portion, is sealed or expanded and flattened and provided with markings or inscriptions, if desired, so as to protect against removal and loss.

The locking seal upon which my present 85 improved press is designed chiefly to operate, (although it may be applied to other uses) passes through the staple 10, or its eye or loop, and partakes of a great variety of different forms for different purposes, uses, and 90 locations, and after being inserted in position has its inserted end subjected to the action of the jaws of the seal press to upset, flatten, spread, or bulge, said end, and if desired to 95 impart a sealing impression or legend thereto, so that this end cannot be withdrawn from the staple without breaking said sealed portion.

One form of this seal, as shown, consists of 100 an incomplete ring 6, having an opening left

at 20 between its ends. The ring is mainly flat with a short half round portion 19. The opening 20 is left between the ends, so that one end of ring 6 may be passed through staple 10, as shown in Figure 1, after the hasp 9 has been shut down over the staple 10; and when so passed through the staple the ring 6 can be adjusted into any position which will enable a portion of the same, as the half round part 19, to be compressed and spread or raised, as at A, between the jaws of the press. A part of ring 6 is preferably enlarged or formed like a broad or flat pad 17, or some similar shape so that some suitable marking, as for example a name or number, may be indicated thereon; and section 17 being longer than the cross-section of the rest of ring 6 which fits the inside of loop 10 will prevent one end of the ring from passing through loop 10. Further ring 6 has an inner notch or indent 18, which is adapted when the ring has been passed through the staple loop 10 far enough, to engage said loop and thus pivot the ring on the loop, whereby the ring is normally centered, permitting it to hang in a position where the opening 20 is opposite to the staple 10. The indent 18 further weakens the ring or seal member 6 at one point, and permits the ring when it is disengaged from the staple to be broken at the notched point if it is desired to break the seal. The press compresses the part 19 of the seal, and some marking or inscription may thus be placed on the compressed part A to distinguish the seal. In Figure 3 the seal 6 is shown prior to being flattened in the press; in Figure 4 the part 19 of the seal is shown as compressed at A, so that the seal then becomes non-withdrawable from the hasp lock.

The bed of the press frame has a base section 1 and second section 2, both being parts of the same casting or bed. On the rear section 2 rests the coin box 7 while the seal 6 is being introduced into the press to be compressed and sealed. To properly align box 7 on bed 2, the latter has an adjustable gauge bar 3, having a projection 3a, the bar 3 being provided with slots 4, 4, that receive thumb screws 5, 5, projecting up from bed 2, and capable of being tightened or loosened, so that several sizes of coin boxes may be gauged in position against bar 3 and its pin 3a to properly project the seal carried on each box forward between the press jaws.

After a box is locked by having the hasp embrace the staple and having one end of the seal passed through the loop of the staple, then the box will be placed on bed 2 close up against the gauge bar 3, and pin 3a, and the seal 6 lifted into a horizontal position, as shown in Figure 1, and directed forward between the jaws of the press. In order to accurately place the seal so that the action of the press thereon will be at the proper point I provide a seal gauge or guide 15 on the die

holding casting 13 that forms a part of the stationary lower jaw casting 12 mounted on bed member 1. Seal guide 15 is a short upright post on casting 13, its upper end being of an inverted V-shape and having opposite vertical grooves 16, 16.

When the seal 6 is directed between the jaws, its open section 20 passes over the V-edge at the top of guide 15 and the two ends of the seal on the opposite sides of opening 20 drop into the grooves 16, and this brings seal 6 into a position where its half round section 19 is directly above the lower die 14a on die member 14 that is held in die frame 13, and also directly below the movable upper die 39 that carries figures or characters to be impressed on the seal, said die 39 being removably held in the lever arm 21, opposite to the lower die 14a. The dies 14a and 39 may vary greatly in form and kind. The die 14a in this example is merely a straight bar on the upper end of a round plug that is held in a socket in casting 13 that forms the front part of the stationary jaw 12; while the die 39 has a round body that is held by a screw or otherwise in the end of the movable jaw arm 21. Said movable arm 21 is pivoted on the stationary jaw 12 by a pivot 11 in bearings 22, 22, on the jaw 12, so that said arm 21 may rock and the movable die 39 be vibrated back and forth with relation to the fixed die, to cause pressure on the seal that is held between them.

The multiple leverage for actuating the movable arm 21 contributes to the ease of movement of the press and comprises the handle 23 and one or more links 30 and accessory toggle joint parts. The jaw casting 12 is extended rearwardly as an angular block 34 that engages a pivot-provided block 35 held securely on block 34 by a screw 36, with shims or spacing plates 37 below block 34 to take up wear.

The lower end of operating handle 23 is pivoted by pivot 29 to the end of lever 21, and also by another pivot 31 to one end of the links 30, the other ends of said links 30 being pivoted by pivot 32 to the block 35 that is solid as shown with the bed of the stationary jaw. Thus the movement of the handle 23 actuates the movable lever 21, and the interposition of the connecting links 30 regulates the character and extent of the throw of the movable arm and the dies. The lower end of the handle 23 is provided with a ratchet segment at 28 adjacent to the pivot 29. The teeth of the ratchet are engaged by the pivoted pawl 27 in a slot in lever 21 and held in position by a flat spring 26, one end of which is secured by screw 40 to the lever 21, while the opposite free end bears against the flat side of pawl 26. The position of the pawl and ratchet is such that the pressing of the seals between the dies is appropriate and regular. And it will be noted that the ratchet

on the handle is so placed that any hand pressure on the handle in the wrong direction will not strip the ratchet teeth. The provision of teeth on the handle differs from the common practice in presses of having the ratchet teeth on the movable die lever.

In Figure 1 the handle is upright, which is the normal position for it to occupy when the machine is idle but is ready to receive a seal to be stamped. At this time the jaws are open, though not to the full width, and the ratchet is out of engagement with the pawl. If now the handle be thrown forward, or to the left, the end of lever 21 nearest the handle will be depressed, which will lift movable die 39 and enlarge the space between the two dies, so that the movable die 39 can be more easily changed, if desired. Also at this time, the toothed end of handle lever 23 will press backwardly against the upright stiff spring 33, the upper end of which may or may not drop into notch 43 near ratchet 28 and this will cause the spring 33 to be flexed more or less and it will hold the handle in its forward position and the dies in the position they assume until the handle is again manipulated. This spring prevents the handle from springing the press partly closed when the seal is pressed and the handle is released quickly. The spring 33 is secured to the stationary part of the frame by the screw 36 which also holds the pivot-provided casting 35 on the stationary jaw member 34, the spring being curved to allow this, and its rear portion rising vertically between the links 30, 30, so that the upper end bears against the lower end of handle 23. If now the handle be forced to the right (after the seal has been located in position between the dies) and brought down to a horizontal position, the ratchet teeth 28 will engage the pawl 27 while the handle is being so moved, and the pawl will prevent any reverse movement of the handle for the time being. This movement of the handle moves the movable die towards the fixed die and registers a flattening, and an impressed character if desired upon the seal. When the handle reaches its limit, and the seal is sufficiently impressed, the handle will strike a stop, consisting of an adjustable screw 25, in a post 24, on bed 1, said screw having a lock nut 41. By again lifting the handle to its idle vertical position the seal will be released from the dies and the coin box can be removed from the press. After the handle 23 reaches a horizontal position in pressing the dies together, the ratchet is released from the pawl so that its teeth will slip idly over the pawl while the leverage is being restored to its former position by lifting the handle 23 to its vertical place again.

A spiral or helical spring 38 is attached to the movable lever 21 and passes down through a recess 42 in the bed 1 where it is

fastened, the function of the spring being to urge the rear part of the movable jaw towards the stationary jaw, and the dies apart, so as to open up the dies after the seal is pressed and the handle is lifted.

It will thus be seen how a hasp seal can be easily applied to the hasp by means of my improved press, and the seal will be effectively pressed and also marked with raised characters. The gauge near the dies insures that the seal will be properly pressed in the exact position that is necessary to make a perfect impression. Many changes in the exact construction and combination may be made without departing from the invention, in so far as this can be done without exceeding the scope of the claim.

What I claim, is:

In a seal press of the class described for impressing ring seals provided with a gap in their peripheries to expose two ends, the combination with the fixed and movable jaws, each having a die, and leverage for actuating the movable jaw, of means adjacent to the dies for positioning the seal accurately between the dies, consisting of a post having an inverted V-shaped upper portion and vertical side grooves, which receive the open portions and the two ends of the seal.

In testimony whereof I hereunto affix my signature.

EMIL DIETZE.
